UNITED STATES PATENT OFFICE.

WILLIAM T. CARROLL, OF WORCESTER, ASSIGNOR TO GEORGE DRAPER & SONS, OF HOPEDALE, MASSACHUSETTS.

SPINDLE-SUPPORT FOR SPINNING-MACHINES.

SPECIFICATION forming part of Letters Patent No. 329,014, dated October 27, 1885.

Application filed November 24, 1884. Serial No. 148,681. (No model.)

To all whom it may concern:

Be it known that I, WILLIAM T. CARROLL, of Worcester city and county, State of Massachusetts, have invented an Improvement in 5 Spindle-Supports for Spinning-Machines, of which the following description, in connection with the accompanying drawings, is a specification, like letters on the drawings representing like parts.

10 This invention in spinning-machines has for its object to improve the support for the spindles, whereby the latter may be run steadily without the employment of bolsters surrounded by elastic or other packings, such as are 15 now commonly used.

My invention consists, essentially, in the combination, with the spindle, of a yielding upright spindle-supporting standard provided at its upper end with a longitudinally-20 arranged chamber for the reception of the foot of the spindle, the sleeve-whirl surrounding the upper end of the said standard, substantially as will be hereinafter described, and as represented in the drawing hereunto annexed.

25 The drawing represents in side elevation a sleeve-whirl spindle and spindle-supporting standard, both broken out at their junction to show the pintle of the spindle entered into the opening at the top of the standard, the 30 usual rail being shown in section, while the securing-nut below it is in elevation.

The rail A, of usual construction, has attached to it by nut A' the spindle-supporting standard B, the upper end of which, extended 35 above the line of the band-pull, is provided with a chamber, in which is placed the pintle of the sleeve-whirl spindle C, the said chamber also receiving oil. The sleeve-whirl surrounds the upper end of the standard, as shown 40 in the drawing, and the bottom of the usual band-groove and the whirl is located at considerable distance below the top of the standard.

In ring-spinning frames it is well known 45 that the bearings for the rapidly-revolving spindles have to be supported in such manner as to permit the loaded spindles to move somewhat in any direction laterally, to thus enable the unevenly-loaded or improperly-balanced 50 spindles to find their true center of rotation, and thus obviate injurious strain or jar of the

parts and the production of bad or imperfect yarn.

In my experiments I have ascertained that by the employment of a long standard, such 55 as shown—a standard nearly or quite as long as the spindle—the necessary amount of elasticity may be readily gained without the employment of elastic packing or an oil or fluid packing such as heretofore used in rapidly-60 rotating spindles.

The spindle C and its attached sleeve-whirl are of usual construction. The standard B in practice is sufficiently rigid to obviate its being bent or deflected by strain due only to 65 band-pull; but the standard is sufficiently flexible to permit its upper end to yield to a limited extent to accommodate for those strains in spinning due to rapid rotation of the spindle with an unbalanced load. The flexible or 70 yielding standard also acts to keep the band taut under usual climatic changes. The standard is provided with a collar, d, attached thereto by a set-screw, e, the said collar serving to sustain the hook f, of usual shape, employed to co-operate with the sleeve-whirl to 75 prevent the withdrawal of the spindle from the standard when doffing the bobbins from the spindles in usual manner.

The bearing for the lower end of the spindle 80 is so far elevated above the flange B' or projection of the standard, which flange bears on the top of the rail A, as to afford between the said bearing and the flange or projection a portion of considerable length which can yield to 85 the requirements of the spindle.

I claim—

1. The rail and the spindle-supporting standard B, erected above it and provided with a flange or projection, B', to rest upon the said 90 rail, and bored at its upper end for the reception of the pintle of the spindle, leaving a yielding portion of the said support between the flange or projection and the lower end of the spindle, combined with a sleeve-whirl spindle having a pintle extended below the sleeve-whirl, the sleeve of the whirl extending down about the upper end of the said standard, substantially as described. 95

2. The rail and the spindle-supporting standard B, provided with a flange or projection, B', to rest on the rail, and bored at its upper 100

end for the reception of the lower end of the spindle, leaving a yielding portion of the said support between the flange or projection and the lower end of the spindle, combined with a 5 sleeve-whirl spindle, the sleeve of the whirl extending down about the upper end of the said standard, and with a hook, *f*, and means to connect it with the spindle, substantially as described.

In testimony whereof I have signed my name to this specification in the presence of two subscribing witnesses.

WILLIAM T. CARROLL.
